UNITED STATES PATENT OFFICE.

JOHN GALBRAITH, OF SWATARA, MINNESOTA.

WOOD-CARVING MACHINE.

1,368,712.

Specification of Letters Patent. Patented Feb. 15, 1921.

Application filed April 23, 1918. Serial No. 230,210.

To all whom it may concern:

Be it known that I, JOHN GALBRAITH, a citizen of the United States, resident of 5 Swatara, county of Aitkin, State of Minnesota, have invented certain new and useful Improvements in Wood-Carving Machines, of which the following is a specification.

The object of my invention is to provide a machine of such construction that universal 10 movement of the tool spindles will be permitted and power transmitted to them with comparatively little loss and with a minimum of belts.

A further object is to provide a machine 15 in which the parts are all nicely balanced, are capable of adjustment on the table for different classes of work and can be easily and quickly manipulated.

The invention consists generally in various 20 constructions and combinations, all as hereinafter described and particularly pointed out in the claims.

In the accompanying drawings forming part of this specification,

25 Fig. 1 is a plan view of a wood carving machine embodying my invention,

Fig. 2 is a side elevation of the machine, a portion of the frame being broken away,

Fig. 3 is a sectional view on the line 3—3 of

30 Fig. 1,

Fig. 4 is a detail view, showing the mechanism through the operation of which universal movement of the tool carrying spindles is permitted,

35 Fig. 5 is a detail view, showing the oscillating hanger through which power is transmitted to the spindles,

Fig. 6 is a detail view, showing an electric motor connected to the belt sheave for driving the spindles.

In the drawing, 2 represents the frame of the machine. 3 is a table having a series of slots 4 therein and mounted on the top of the frame to form a bed for the work. 45 This table is of ordinary construction, but I prefer to make it stationary on the frame instead of movable, as usual in machines of this type.

On each side of the machine frame I provide 50 brackets 5 and rods 6 arranged in parallel relation and secured in said brackets, and above said rods and parallel therewith are screw shafts 7, also secured in said brackets.

A carrier 8 has anti-friction wheels 9 to rest 55 and roll on the rod 6 and also has sleeves 10 interiorly threaded to engage the threads

of the screw shaft 7, and these sleeves are revolved by means of sprocket-belts 11 connecting them with a stub shaft 12 centrally mounted on a cross bar 13 of the carriage 60 and having an operating wheel 14. By revolving this wheel, the machine attendant can move the carriage back and forth on the screw shaft 7 over the table.

Upon the carriage 8 I provide brackets 65 15 and 16 having bearings for upright shafts 17. The upper ends of these shafts have beveled gears 18 meshing with pinions 19 on a cross shaft 20 and one end of said shaft 20 has an operating wheel 21 by means of 70 which the said upright shafts may be revolved. The lower portion of these upright shafts have threads formed thereon and brackets 22 have arms 23 and 24 thereon, the former being interiorly threaded to engage 75 the threads of the shaft 17 while the latter slide freely on the upper portions of said shafts. When, therefore, the shafts 17 are revolved, the brackets 22 will be raised or lowered, as desired.

At the inner ends of the brackets 22 I provide members 25, each in the form of a double T provided with pairs of arms 26 and 27, the arms of each pair being in parallel relation and the arms 26 having pivot pins 28 85 mounted therein between which the inner ends of the brackets 22 are inserted to form bearings for said pins. The arms 27 have similar pivot pins for blocks 28' which are inserted between them and centrally pivoted 90 at 29 to the walls of a pipe 30, which extends transversely of the machine between the end rails of the carriage. This pipe may, therefore, oscillate longitudinally or transversely 95 of the machine on the vertical pivots 28 and also has a vertical movement on the horizontal pivots 29. A shaft 30' is mounted in bearings on the carriage transversely of the machine and has depending arms 31 pivotally connected by links 32 with the lower 100 walls of the pipe 30 and rods 33 are mounted on the shaft 30' and provided with counter-balance weights 34. Brackets 35 have loop portions 36 to receive the ends of the pipe 30 and bearings 37 are mounted on said pipe 105 for pivot pins 38 carried by the loops 36 and forming vertical pivots on which the said brackets 35 may oscillate transversely of the machine.

At the forward ends of the brackets 35 is 110 a cross bar 39 in which a series of tool-carrying spindles 40 are mounted, said bar 39

being preferably in the form of a channel and provided with sheaves 41. The brackets 35 and the tool spindles supported thereby are counter-balanced by means of weights 5 41' mounted on rods 41" carried by the looped portion 36 of the brackets 35 on the opposite side of the pivots from the tool spindles.

- 10 On the underside of the pipe 30 at each end thereof I provide sheaves 42 having belt surfaces 43 and 44 separated by a rib 45 and also having preferably on the same hub a smaller belt surface 46. These sheaves are secured to the underside of the pipe 30 by means of studs 47 having threaded ends to enter threaded sockets in pins 48 which are mounted in the pipe 30 and have projecting ends for engagement of a tool therewith for tightening or loosening purposes. These 15 sheaves 42 turn freely on the studs 47 for the transmission of power to the tool spindles.

For driving the sheaves 42 I provide belts 49 for the pulleys 46 extending to sheaves 25 50 having running connections with the sheaves on the surfaces 46 and extending to pulleys 50 carried by rods 51 which are pivoted at 52 in brackets 53. Pulleys 54 30 are supported by the brackets 53 and have belts 56 connecting them with the pulleys 50 and belts 57 connecting the pulleys 54 with a suitable source of motive power. The lower ends of the rods 51 are provided with rods 58 pivotally supported thereon and 35 pivoted at 59 to pins 60 mounted in the walls of the pipe 30. These pivotal connections allow the pipe to be oscillated forward and backward or up and down to follow the different positions of the tool spindles.

Between the sheaves 42 and the pulleys on the tool spindles I provide driving belts 61; these belts having running connections with the pulleys 42 on the surfaces 43 and 45 44, so that a single belt carried back and forth will operate two spindles which are preferably arranged as shown in the plan view, two at each end of the bar 39, with a master or tracing tool 62 in the center of 50 the bar between them.

Suitable belt tightening devices 65 are provided for the belts 61 and similar tighteners 66 are mounted on the rods 58 for engaging the belts 49.

55 In Fig. 6 I have shown a modification which consists in mounting an electric motor 67 on the top of the pipe 30 and extending its shaft 68 down through the pipe and mounting the pulley 42 on the lower end 60 of this shaft and then belting direct from this pulley in the manner shown to the tool spindles. In this case there would, of course, be an electric motor at each end of the pipe 30.

65 The operation of the machine is as fol-

lows: The slotted table on which the work is placed is stationary. The carriage supporting the tool spindle carrier is adjusted forward or backward over the table for the desired operating position and the carrier 70 through the medium of its pivotal supports on the carriage will be free to swing forward or backward and laterally to position the tools with respect to the work. The depending hanger through which power 75 is transmitted will follow the carriage back and forth so that regardless of the position of the carriage over the table, the belts will transmit power to the tool carrying spindles. The carriage is counter-balanced 80 so that it can be easily moved back and forth or from side to side, according to the position of the work on the table.

I claim as my invention:

1. The combination, with a frame and a 85 table mounted thereon, of a carriage mounted for forward and backward movement over said table, a carrier, upright shafts whereon said carrier is vertically adjustable, brackets having vertical pivots on said carrier, tool holders mounted in said brackets and means for operating said tool holders.

2. A wood carving machine comprising a frame, a stationary table mounted thereon, a carriage mounted for movement back and 95 forth over said table, a transverse member mounted for horizontal oscillation and vertical adjustment in said carriage, a tool carrier supported by said member and mounted for universal movement, and means for 100 operating said tool carrier.

3. A wood carving machine comprising a frame, a stationary table mounted therein, a carriage mounted for movement forward and back over said table, a transverse member 105 mounted for horizontal oscillation and vertical adjustment in said carriage, a carrier mounted in said member for universal movement over said table, and having a plurality of tool-carrying spindles, and an oscillating hanger having pivotal connections with said spindles.

4. The combination, with a frame, of a stationary table mounted therein, a carriage mounted for movement forward and back 115 over said table, brackets mounted in said carriage for horizontal oscillation and vertical adjustment, a transverse member having bearings in said brackets, a plurality of tool-carrying spindles supported by said 120 transverse member, pulleys mounted on said member and driving belts connecting said pulleys with a source of motive power and with pulleys on said spindles.

5. The combination, with a frame and a 125 table mounted thereon, of a carriage mounted for forward and backward movement over said table, upright spindles journaled in said carriage and having threaded portions, brackets mounted for oscillation on 130

5 said upright spindles and engaging the threaded portions thereof for vertical adjustment thereon, means for revolving said spindles, a carrier supported by said bracket for universal movement and having a plurality of tool holders, and means for operating said tool holders.

6. The combination, with a frame, of a table mounted therein, a carriage mounted 10 for forward and backward movement over said table, brackets carried by said carriage for horizontal oscillation, double T-heads having vertical pivots on said brackets, blocks having vertical pivots on said heads, 15 a floating cross member having horizontal pivots on said blocks, a counter-balancing means for said floating cross member, brackets having vertical pivots on said floating cross member and projecting forwardly over 20 said table and having a plurality of tool holders, counter-balancing means for said tool holder brackets, and means for driving said tool holders.

7. The combination, with a frame, of a 25 table mounted thereon, a carriage mounted for forward and backward movement over said table, a floating transverse member pivotally supported by said carriage, brackets having loop portions encircling said member and having vertical pivots thereon, said brackets projecting forwardly over said table and provided with a plurality of tool 30 holders, a counter-balancing means for said brackets projecting rearwardly of said floating member, and means for driving said tool 35 holders.

8. In a wood carving machine, the combination, with a transverse floating member having horizontal and vertical pivots 40 and a counter-balancing means therefor, of brackets having vertical pivots on said floating member and projecting forwardly therefrom and provided with a plurality of tool spindles, a counter balancing means for said brackets, pulleys mounted on said floating member, an oscillating hanger and a driven pulley supported therein and having belt connections with the pulleys of said floating member, and driving belts extending 45 from the pulleys of said floating member to said tool spindles.

9. In a wood carving machine, the combination, with a transverse member having horizontal supporting pivots and counter 55 balances for said member, brackets having vertical pivots on said member and projecting forwardly therefrom and provided with tool carrying spindles arranged in pairs, pulleys supported by said member and having double faces and single belts connecting the double faces of said belts with the pairs respectively of said spindles, and means for driving said pulleys.

10. In a wood carving machine, the combination, with brackets mounted to oscillate 60

in a horizontal plane, double T-heads having vertical pivots on said brackets, blocks having vertical pivots on said T-heads, a transversely arranged floating member having horizontal pivots on said blocks, and counter-balances for said member, and a carriage having tool spindles mounted therein and provided with vertical pivots on said floating member, counter-balances for said carriage, and means for driving said spindles.

11. The combination, with a frame, of a table mounted thereon, a carriage mounted for forward and backward movement on 80 said table, a transverse member having horizontal and vertical pivots on said carriage for vertical and horizontal oscillation thereon, brackets having vertical pivots on said member and projecting over said table and provided with tool holders, and counter- 85 balancing means for said brackets and means for driving said tool holders.

12. The combination, with a frame, of a table mounted thereon, a carriage mounted for forward and backward movement on 90 said table, a transverse member having vertical and horizontal pivotal supports in said carriage, brackets mounted for horizontal oscillation on said member and provided with tool holders, a counter-balancing means 95 for said brackets on the opposite side of said member and means for driving said tool holders.

13. The combination, with a frame, of a table mounted thereon, a carriage mounted 100 for forward and backward movement on said table, brackets mounted in said carriage for horizontal oscillation, heads having vertical pivots on said brackets, a pivoted cross member supported by said heads 105 for vertical oscillation, a counter-balancing means for said member, a tool holder, brackets mounted for horizontal oscillation on said member and projecting forwardly over 110 said table, and means for driving said tool holders.

14. In a wood carving machine, the combination with a transverse member having horizontal and vertical supporting pivots and counter-balances for said member, 115 brackets pivoted on said member and provided with tool carrying spindles, pulleys supported by said member, belts connecting said pulleys with said spindles respectively, an oscillating hanger, and a driven pulley 120 mounted therein and having belt connections with the pulleys of said transverse member.

15. The combination, with a frame, of a table mounted therein, a carriage mounted 125 for forward and backward movement on said table, a member transversely supported in said carriage and mounted to oscillate horizontally and vertically therein, brackets mounted for oscillation with said mem- 130

ber and independently thereof and provided with tool holders, and counter-balancing means for said brackets, and means for driving said tool holders.

5 16. The combination, with a frame, of a table mounted therein, a carriage mounted for forward and backward movement on said table, a member transversely supported in said carriage and mounted to oscillate horizontally and vertically therein, brackets mounted for oscillation with said member and independently thereof and provided with tool holders, and counter-balancing means for said brackets, an oscillating hanger, a driven pulley mounted therein and driving connection between said pulley and said tool holders.

10 17. The combination, in a wood carving machine with a transversely arranged floating member mounted to oscillate horizontally and vertically and a counter-balancing means therefor, of brackets pivotally supported on said member and provided with a plurality of tool holders arranged in pairs, pulleys supported by said member and having double faces and belts connecting the

15 double faces of said pulleys with the pairs respectively of said spindles, and means for driving said pulleys.

18. A wood carving machine comprising a frame, a stationary table mounted therein, a carriage mounted for movement forward and back over said table, a member mounted in said carriage for universal movement over said table, a tool carrier mounted for oscillation on said member and having a tool-carrying spindle, and means for driving said spindle.

19. A wood carving machine comprising a frame, a stationary table mounted therein, a carriage mounted for movement forward and back over said table, a member mounted in said carriage for universal movement over said table, a tool carrier mounted for oscillation on said member and having a tool-carrying spindle, and an oscillating hanger having belt connections with said spindle.

In witness whereof, I have hereunto set my hand this 8th day of April, 1918.

JOHN GALBRAITH.
